[57] CLAIM

The ornamental design for a toilet paper roll holder for toilet tank attachment, as shown and described.

DESCRIPTION

FIG. 1 is a perspective view of the toilet paper roll holder for toilet tank attachment showing my new design;

FIG. 2 is a rear elevational view thereof;

FIG. 3 is a top plan view thereof; and

FIG. 4 is a reduced right side elevational view thereof, the left side being a mirror image of that shown.

FIG. 1

FIG. 3
